UNITED STATES PATENT OFFICE.

WILLIAM S. ARNOLD, OF LORAIN, OHIO.

TROLLEY-WIRE HANGER.

No. 905,976.

Specification of Letters Patent.

Patented Dec. 8, 1908.

Application filed June 18, 1908. Serial No. 439,148.

To all whom it may concern:

Be it known that I, WILLIAM S. ARNOLD, citizen of the United States, residing at Lorain, in the county of Lorain and State of Ohio, have invented certain new and useful Improvements in Trolley-Wire Hangers, of which the following is a specification.

This invention relates to improvements in trolley wire hangers or supports.

10 One of the objects of my invention is the provision of a hanger which is inexpensive to manufacture, and which will support the trolley wire in an effective manner, and at the same time permit the latter to have free 15 movement relative to the spanner or supporting wire both laterally and in a vertical plane so that the passage of the trolley along the wire will not cause the trolley wire to be worn or broken at the ends of the 20 clamping portion of the hanger.

A further object is to provide a construction such that the use of cast metal parts can be entirely done away with.

The hanger constructed in accordance 25 with my invention is composed principally of two parts, a supporting member which engages the spanner wire and a trolley wire clamping member which is freely supported from the supporting member, the construction of said parts being such that each can be formed from a single piece of sheet metal.

The supporting member which engages the spanner wire is provided at the top with spaced oppositely bent hooks which receive 35 the spanner wire and which are out of alignment so that the said wire is slightly bent or kinked and can not work out of place, and with a socket or sleeve portion which receives firmly an insulated bolt or rod which 40 supports the trolley wire clamping member. The other member which engages the trolley wire is preferably formed by doubling a plate upon itself, the trolley wire being clamped between the free ends of the plate 45 by bolts passing through the latter and is provided at the top with an opening through which the lower end of the bolt carried by the supporting member passes freely, the clamping member being retained on the bolt 50 by some means such as a nut on the end of the bolt.

My invention may be further briefly summarized as consisting in certain novel details of construction and combinations and 55 arrangements of parts which will be de-

scribed in the specification and set forth in the appended claims.

Reference is now had to the figures of the drawing, in which

Figure 1 is a side elevation of a hanger 60 constructed in accordance with my invention showing a portion of a trolley wire and also a portion of the supporting wire, and the dotted lines showing a position which the hanger may assume when rocked by the trolley of a passing car, Fig. 2 is a side view taken at right angles to the view shown in Fig. 1; Fig. 3 is a vertical sectional view; and Fig. 4 is a plan view.

In carrying out my invention any preferred form and construction of parts may be employed as long as they possess the necessary characteristics, but in the drawings I have shown one embodiment which meets the requirements very effectively, and 70 in said embodiment 1 represents as a whole the supporting member or the part which engages the spanner or supporting wire, and 2 the clamping member or the part which engages the trolley wire. The member 1 is 80 formed in this case from a single sheet of metal and is provided at the top with a pair of oppositely extending arms 3 and 4 having at the ends hooks 5 and 6 bent in the same direction, and at the center midway between 85 the hooks 5 and 6 is a hook 7 out of line with the hooks 5 and 6 and bent in an opposite direction. These hooks receive the spanner or supporting wire 8 which is bent or slightly kinked and is therefore in no danger 90 of working out of place.

Below the hooks is a hollow socket or sleeve like portion 9 formed by bending two wings 10 and 11 toward each other so as to form a hollow cylinder. This socket portion 95 receives with a tight fit an insulator 12 in the form of a spool which may be formed in any desired manner, but in the present case is formed of a number of disks or washers of insulating material. Passing through the 100 center of the insulating spool is a member which supports the trolley wire clamping member 2, and in the present instance this member is in the form of a bolt 13 provided at its upper end with a nut 13^a which is 105 clamped down on the upper disk of the spool 12 and having its lower end projecting below the spool.

The member 2 is formed from a single piece of sheet metal doubled upon itself and 110

- being substantially U-shaped, having two side portions 14 and 15 and a top portion 16. This member 2 is supported on the bolt 13 which passes loosely through a centrally located opening in the top portion 16 and is provided on the under side of the top portion 16 with a retaining member which is, in this case, a nut 17 engaging the threaded end of the bolt. The lower edges of the side portions of the member 2 are beveled and said portions are slightly rounded outward near the edges as shown at 18 and 19. These rounded portions receive the trolley wire 20 and are clamped firmly about the same by clamping bolts 21 which extend between the sides of the member 2, the latter being slightly bulged or curved outward at this point. The clamping member 2 is preferably made from material having considerable spring or elasticity so that there will always be sufficient pressure on the nuts 22 of the bolts 21 to prevent the nuts turning, and at the same time the trolley wire will be held firmly in place. The edges of the nut 17 are slightly rounded and the size of the nut and bolt are such as to permit the clamping member 2 to have a rocking movement both laterally and in a vertical plane so that there is little danger of the trolley wire being broken or worn at the corners of the clamping portion of the side plates when the trolley of a car passes along the wire. The nut is of course sufficiently large to prevent its working off the bolt.
- 35 I do not desire to be confined to the exact details shown but aim in my claims to cover all modifications, which do not involve a departure from the spirit and scope of my invention.
- 40 What I claim as new and desire to secure by Letters Patent is:
1. In a trolley wire hanger, a supporting member formed of a single piece of metal and having a socket portion and hooks 45 which are bent in opposite directions and are out of alinement with one another, said hooks being adapted to receive a spanner or supporting wire, an insulated bolt carried by said socket portion, and a trolley wire clamping member mounted upon the lower end of the bolt.
  2. In a trolley wire hanger, a supporting member formed of a single piece of sheet metal, said member having a portion bent in the form of a sleeve or socket and having oppositely extending arms or wings having hooks bent in one direction and having intermediate said hooks and out of alinement therewith a hook bent in the opposite direction, said hooks being adapted to receive a supporting wire, an insulated bolt carried by said sleeve or socket portion and a trolley wire clamping member carried by the lower end of said bolt.
  3. In a trolley wire hanger, a supporting member adapted to be connected to a spanner or supporting wire, an insulated supporting bolt carried by said member, a trolley wire clamping member consisting of a piece of metal doubled upon itself forming side portions adapted to receive a trolley wire and means for clamping said side portions about the trolley wire consisting of bolts passing through the former, said supporting bolt passing through the top of said clamping member and having retaining means at the lower end thereof and on the interior of the clamping member.
  4. In a trolley wire hanger, a supporting member adapted to be connected to a spanner or supporting wire, an insulated supporting bolt carried by said member, a trolley wire clamping member consisting of a plate doubled upon itself forming free side portions which receive the trolley wire, means for clamping said side portions against said trolley wire, said supporting bolt passing freely through the top of said clamping member and having on the interior thereof a retaining nut.
- 50 55 60 65 70 75 80 85 90 95
- In testimony whereof I affix my signature in presence of two witnesses.
- WILLIAM S. ARNOLD.
